UNITED STATES PATENT OFFICE.

EMANUEL AUFIERO, OF BROOKLYN, NEW YORK.

DESIGN FOR A WARNING-SIGNAL.

52,941.

Specification for Design.

Patented Feb. 4, 1919.

Application filed July 14, 1917. Serial No. 180,667. Term of patent 14 years.

To all whom it may concern:

Be it known that I, EMANUEL AUFIERO, a citizen of the United States, residing in the borough of Brooklyn, county of Kings, city and State of New York, have invented a new, original, and ornamental Design for Warning-Signals, of which the following is a specification, reference being had to the accompanying model and drawing, forming part thereof.

In the said drawing,

Figure 1 is a perspective view of my warning signal;

Fig. 2 is a front elevation; and

Fig. 3 is a side elevation thereof.

The front plate A of the horn is usually finished to a bright polished metal surface, while the body B of the horn and bracket are preferably enameled.

I claim:

The ornamental design for a warning signal as shown and described.

EMANUEL AUFIERO.
